UNITED STATES PATENT OFFICE.

ROBERT S. SHARP, OF NEW YORK, N. Y., ASSIGNOR TO NATIONAL TAPE COMPANY, INC., OF NEW YORK, N. Y., A CORPORATION OF NEW YORK.

HOLDER FOR TAPE-WOUND CONES AND THE LIKE.

1,154,443.

Specification of Letters Patent.

Patented Sept. 21, 1915.

Application filed February 10, 1914. Serial No. 817,754.

To all whom it may concern:

Be it known that I, ROBERT S. SHARP, a citizen of the United States, residing at New York city, in the county of New York and State of New York, have invented certain new and useful Improvements in Holders for Tape-Wound Cones and the like, of which the following is a specification, reference being had therein to the accompanying drawing.

This invention relates to holding devices for cops, cones or spools wound with tape, ribbon, or the like.

The object of the invention is to provide an inexpensive but practical and efficient holder of the class specified, whereby tape, or the like, on the cone supported thereon may conveniently be unwound therefrom without strain and with entire elimination of any tendency to twist.

A further object is so to construct the device that the tape-wound cone or cop may readily be mounted in the holder and replaced from time to time, and this without necessity of employing tools.

With these and other objects in view, the invention resides in various novel arrangements and combination of instrumentalities, all as hereinafter more fully described and claimed.

In the accompanying drawings, forming a part hereof, I have exemplified one of many possible embodiments of my invention; it being understood that the same is susceptible of a wide range of modification without departure from the spirit and the principles of the inventive concept.

In these drawings: Figure 1 is a view in perspective of a holder constructed in accordance with my invention; the parts of the structure being, in this instance, shown as unassembled; Fig. 2 is a view in horizontal section (with portions broken away to show certain details) of the base-plate forming a component of the holder; Fig. 3 is a view in central vertical section of the holder, the parts being, in this instance, in their assembled positions; and Figs. 4 and 5 are views also in central vertical section, showing modified forms of cone-supporting members with cones disposed thereon.

Referring to the drawings, the reference-numeral 1 designates a base-member which may be of wood or any other appropriate material and dimensions. Preferably and

as shown, this base-member is formed with an upstanding circumferential flange 2 of a height sufficient to afford substantial strength thereto. In the inside wall of this flange are formed incuts or recesses 3, for a purpose presently to be explained. The base-member is also provided with a central recess 4 having a substantially flat bottom and vertical walls. In the center of this recess, a countersunk hole 5 is provided for a screw 6 whereby the base-member may be rotatably attached to any suitable surface, such as the top of a counter 7.

In the embodiment illustrated, by way of example, an arch-member 8 is adapted to be removably mounted on the base-member. In this instance, this arch-member is disclosed as comprising a horizontal portion 9 provided with an aperture 10, and two vertical portions 11 having angulated ends 12. One of the vertical portions is also provided with an elongated guide-slot 13. The angulated ends are adapted to extend into the recesses or incuts 3 in the flange of the base-member, as shown in Fig. 3. This arch-member may be of any required dimensions and material; but, preferably, I construct it so that it is somewhat resilient though, generally speaking, it possesses considerable rigidity.

The arch-member has, as one of its special functions, to sustain a cone-supporting member, spindle or core 14 which, in this instance, is preferably tapered so as to fit a cone 15 wound with tape or the like. The spindle or core 14, at its base, is formed to provide a cylindrical portion 16 that is adapted to be seated in the recess 4. Although its cylindrical wall parallels, and is surrounded by, the wall of the recess, nevertheless, the core is free to rotate therein. At its upper end, the core is, preferably and as shown, provided with a pin or pintle 17 adapted to extend into the aperture 10 in the aforementioned horizontal portion of the arch-member.

In the type of core shown in Figs. 1, 2 and 3, the surface of the core is so formed as to be engaged by a very substantial portion of the inside wall of the cone. In Fig. 4, however, the surface 18 of the spindle or core is concaved, as shown, so that the cone engages it only at and is suspended from its upper end. In some cases, this is an advantageous arrangement, since the space be-

tween the exterior wall of the core and the interior wall of the cone would allow for any unevenness in the cone—due, for instance, to the tape being wound very tightly and thereby effecting a slight distortion or deformation of the cone. In Fig. 5, the spindle or core is somewhat similarly formed; but, in this instance, the cone engages the core at 19, adjacent its lower end as well as at 20 adjacent its upper end.

10 In assembling the parts, as shown in Fig. 3, the spindle or core is seated in its recess 4, and the cone of tape is then placed thereon; or, if preferred, the cone may first be placed on the core and the latter then seated in its aforementioned recess. Thereupon, one leg of the arch-member 8 is placed so that its angulated end 12 can be inserted into its respective recess. Just preceding this operation (or simultaneously therewith, if preferred), the horizontal portion of the arch-member is positioned over the upper pin-carrying end of the core. Then the other leg of the arch-member is positioned so that its angulated end may extend into its recess. It will be noted that these angulated ends are so dimensioned—and similarly their respective recesses—that there is provided a comparatively close fit of the end 25 within its recess. By this means, the arch-member is held rigidly on the base and it, in turn, sustains the core and its cone against accidental displacement and even against undesirable movement. It is to be understood, however, that the core is free to rotate in its recess. Moreover, the spindle or core is, preferably, surfaced so that the cone may have free rotation thereon. In other words, the core is adapted to have rotative movement either with or independently of the cone; and, likewise, the cone can rotate on the core or with it. The desideratum here is to arrange for movement of one or the other, or both, of these components, so 30 that, as the portion 21 of the tape is being drawn off and through the guide-slot 13, it will do so without undue binding and without twisting. The rotative movement of the cone on the spindle,—or of the core and spindle together—permits the unwinding of the tape without any twisting of the same. The guide-slot also facilitates the withdrawal of the tape from its cone. It will be observed that the lower end of the cone does 35 not extend quite down to the upper surface of the base-member, nor should it because it would then tend to engage it and, thus, be held against free rotation.

In the event that a loop or portion of the 40 tape should drop down and wind around the core or cone—below the lower surface of the mass of wound tape—said loop will simply effect a turning of one or another (or both) of these elements and, almost instantly, continue to unwind properly from

its cone. It is of the essence of the invention that the core or cone shall have free rotation so that the tape will unwind from the cone as it rotates—rotates in a direction directly opposite that in which it moved when 70 the tape was being wound thereon. It will therefore be understood that the core and cone may rotate independently of each other or in unison one with the other. By arranging to have the base-member free to rotate on its axis—that is, on the screw 6—it will position the arch-member and its slot 13 in any desired direction.

75 While I have herein described my invention in detail, nevertheless it is to be understood that I do not limit myself to such details except in so far as they may be specified in the appended claims.

80 What I claim is:

85 1. A holding-structure including in combination, a base-member provided with an approximately central recess and with side recesses, an arch-member upstanding from the base-member and having its ends angulated to engage in said side recesses, and a supporting member rotatably disposed in said central recess and connected at its upper end to said arch-member.

90 2. A holder including in combination, a base-member provided with a central recess and having an upstanding circumferential flange provided with recesses; an arch-member comprising converging vertical portions one of which is provided with an elongated slot and both of which are provided with 95 angulated ends adapted to engage in the flange-recesses, and a horizontal portion provided with an aperture intermediate its juncture with said vertical portions; and a cone-supporting member removably disposed in said central recess and having its upper end extending into said aperture and rotatively sustained by the arch-member.

100 3. A holder including in combination, a base-member provided with a central recess having a substantially vertical wall and having an upstanding circumferential flange provided with recesses; an arch-member comprising converging vertical portions one of which is provided with an elongated slot 115 and both of which are provided with angulated ends adapted to engage in the flange-recesses, and a horizontal portion provided with an aperture intermediate its juncture with said vertical portions; and a cone-supporting member removably disposed in said central recess and having its lower end provided with a relatively cylindrical portion adapted to present a surface substantially parallel to the vertical wall of said recess 120 and having its upper end extending into said aperture and rotatively sustained by the arch-member.

125 4. A holder including in combination, a base-member provided with a central recess 130

and a screw-hole communicating with the recess and having a circumferential flange provided with recesses; an arch-member provided with outstanding portions adapted 5 to extend into said flange-recesses; a cone-supporting member having its lower end disposed in said central recess and its upper end connected to the arch-member and rotatably sustained thereby; and a tubular 10 tape-wound cone rotatively supported on said cone-supporting member.

5. A holder including in combination, a base-member provided with a central recess and a screw-hole communicating with the 15 recess and having a circumferential flange

provided with recesses; an arch-member provided with outstanding portions adapted to extend into said flange-recesses; a tapered cone-supporting member having its lower end disposed in said central recess and its 20 upper end connected to the arch-member and rotatably sustained thereby; and a tubular tape-wound cone rotatively supported on said cone-supporting member.

In testimony whereof I affix my signature 25 in presence of two witnesses.

ROBERT S. SHARP.
